SELF-PROPELLED ROTATABLE HYDRAULIC CRANE

John L. Grove, 171 Apple Drive, Greencastle, Pa.

Filed July 2, 1965, Ser. No. 86,006

Term of patent 14 years

(Cl. D14—3)

FIG.1

FIG.5

FIG.6

FIG. 2

FIG. 3

FIG. 4

FIG. 1 is a side elevational view of a self-propelled rotatable hydraulic crane showing my new design, shown in traveling position;

FIG. 2 is a top plan view thereof;

FIG. 3 is a front elevational view thereof;

FIG. 4 is a rear elevational view thereof;

FIG. 5 is a side elevational view showing the side of the self-propelled vehicle opposite that of FIG. 1 and the same side of the hydraulic crane of FIG. 1 in rotated position and in extended and elevated working position; and

FIG. 6 is a side elevational view showing the same side of the self-propelled vehicle as in FIG. 5 and the hydraulic crane rotated to show the side thereof in working position opposite that shown in FIG. 5.

I claim:

The ornamental design for a self-propelled rotatable hydraulic crane, substantially as shown and described.
